UNITED STATES PATENT OFFICE.

THOMAS H. ROYCE, OF BROOKLYN, ASSIGNOR TO BENJAMIN ALTMAN, OF NEW YORK, N. Y.

DESIGN FOR A PATTERN FOR BICYCLE GARMENTS.

SPECIFICATION forming part of Design No. 25,191, dated February 18, 1896.

Application filed January 11, 1896. Serial No. 575,180. Term of patent 14 years.

To all whom it may concern:

Be it known that I, THOMAS H. ROYCE, a citizen of the United States, residing in Brooklyn, Kings county, State of New York, have 5 invented and produced a new and original Design for a Pattern for Bicycle Garments, of which the following is a specification.

The leading feature of my design is a pattern for bicycle garments of substantially the 10 outline illustrated in the accompanying drawing, which shows my design.

In the drawing, A is a bicycle-skirt pattern

which is bounded by the curved gored edge *a*, the radial edges *b* and *c*, which are joined by the curved edges *d e*, whose continuity is 15 broken by gores *f*.

What I claim is—

The design for a pattern for a bicycle garment, substantially as herein shown and described.

THOMAS H. ROYCE.
